UNITED STATES PATENT OFFICE.

FREELAND W. JUDSON, OF CLEVELAND, OHIO.

RUNNING-GEAR FOR STREET-CARS.

SPECIFICATION forming part of Letters Patent No. 425,380, dated April 8, 1890.

Application filed February 15, 1890. Serial No. 340,561. (No model.)

To all whom it may concern:

Be it known that I, FREELAND W. JUDSON, of Cleveland, in the county of Cuyahoga and State of Ohio, have invented certain new and useful Improvements in Running-Gear for Street-Cars; and I do hereby declare the following to be a full, clear, and exact description of the invention, such as will enable others skilled in the art to which it pertains to make and use the same.

My invention relates to improvements in running-gear for street-cars; and it consists in certain features of construction and in combination of parts hereinafter described, and pointed out in the claims.

In the accompanying drawings, Figure 1 is a side elevation, portions of the housing being broken away to show the construction. Fig. 2 is an end elevation in detail. Fig. 3 is a view in perspective in detail.

A represents the body of the car, constructed in the usual manner, with longitudinal sills A'.

B B are the car-wheels, and B' B' are the housings for the axle-journal boxes b b.

C C are the primary levers, supposed to be alike and of considerable length, and arranged in pairs on either side of the car and located under the car-sills, the one section of

each lever being bent upward, as shown, to constitute a yoke C', these yokes being adapted to extend over and ride astride a journal-box b but having, preferably, a rubber block or spring b' interposed between box b and the opposing section of the yoke. The outer ends of each lever C bear against a spring c, the latter in turn bearing against the under side of the car-sill, or, rather, bearing against a suitable seat a, the latter being attached to

the car-sill. It will be observed that the two springs c on the same side of the car are widely separated and are comparatively near the end of the car-body. The inner ends of the two levers C C, located on the same side

of the car, are connected by means of links d with the extreme of an equalizing-lever D. The two levers D of opposite sides of the car are connected by means of a cross-bar F. The reduced end sections of bar F extend

50 with an easy fit through lateral holes made at the center of levers D D.

E is a flat bar connecting the two housings on the same side of the car, and on top and

midway of bar E is secured a metal block E', this block having four lugs e, extending upward, as shown more clearly in Fig. 3, with spaces between the lugs for receiving loosely lever D and cross-bar F. Block E' and attachments are for holding lever D and bar F in place, and does not sustain any weight save its own.

G is a heavy spring, one of which is provided for each lever D. This spring rests on a suitable seat g, attached at the longitudinal center of lever D. The upper end of spring G engages seat a', the latter being secured to the car-sill. Although bar F fits loosely in levers D D, so that the levers may rock on this bar as an axle independent of each other, still the cross-bar prevents levers D from tilting laterally, and in case electric motors are placed on the car bar F is in position to support the inner ends of the motors.

With the construction shown, and by means of levers C and D and the springs distributed as shown, the car in a great measure is prevented from rocking, and hence rides very easily, and the car-wheels in passing over obstructions or over inequalities of the track affect the car much less than with the various constructions heretofore employed.

What I claim is—

1. In running-gear for street-cars, the combination, with primary levers arranged in pairs lengthwise the car and adapted, respectively, to ride on the journal-boxes of the car-axle, of a bar connecting the housings of the axle-journals, equalizing-levers fulcrumed on said bars, the extremes thereof being operatively connected with the inner end of the primary levers, and springs located, respectively, at the center of the equalizing-lever and at the extremes of the pair of primary levers, the different springs engaging the car-body, substantially as and for the purpose set forth.

2. The combination of primary and equalizing levers and springs, substantially as indicated, of cross-bar engaging the respective equalizing-levers, substantially as set forth.

In testimony whereof I sign this specification, in the presence of two witnesses, this 18th day of January, 1890.

FREELAND W. JUDSON.
